US00D495348S1

(12) **United States Design Patent** (10) Patent No.: **US D495,348 S**
Brasseur (45) Date of Patent: **** Aug. 31, 2004**

(54) **OHMIC CLIP**

(75) Inventor: **Jonathan Brasseur**, Cornish, NH (US)

(73) Assignee: **Thermal Dynamics Corporation**, West Lebanon, NH (US)

(**) Term: **14 Years**

(21) Appl. No.: **29/167,079**

(22) Filed: **Sep. 9, 2002**

(51) LOC (7) Cl. **15-09**

(52) U.S. Cl. **D15/144; D8/395**

(58) Field of Search **D15/144, 144.1, D15/144.2; D8/30, 70, 394, 395, 396; D7/620, D12/420, 421; 219/121.11, 121.48, 121.49, 121.51, 121.52, 121.53, 121.54, 121.55, 121.56, 121.57, 121.58, 121.59, 158; 24/455, 457; 248/200, 220.1, 228.7, 229.16, 229.26, 230.7, 230.72, 231.81, 300**
